United States Patent Office

Des. 190,844
Patented July 4, 1961

190,844

AIR HEATER

John T. Armbruster, Niagara Falls, N.Y., assignor to
American Optical Company, Southbridge, Mass., a
voluntary association of Massachusetts

Filed Sept. 15, 1960, Ser. No. 62,144

Term of patent 14 years

(Cl. D81—10)

fig. 1

fig. 2

fig. 3

FIG. 1 is a top plan view of an air heater embodying my new design;

FIG. 2 is a side elevational view thereof, the opposite side being substantially the same;

FIG. 3 is an end elevational view thereof as seen from the left of FIG. 2, the opposite end being substantially plain.

The dominant features of my new design are shown by full lines in the drawings.

I claim:

The ornamental design for an air heater, substantially as shown and described.
